SURFACE MOUNTED CLOSURE REMOVER
WITH CLOSURE RETAINING MEANS

Isaac A. Morris, Clifton Springs, N. Y.

Application October 21, 1952, Serial No. 315,926

6 Claims. (Cl. 81—3.1)

1

This invention relates to devices for removing crown caps from bottles and of the type adapted to be mounted in fixed position on a supporting surface, such as a vertical wall. More particularly, the invention is concerned with a novel decapper, which is of simple, inexpensive construction and easy to operate and is provided with magnetic means for holding each cap as it is released from its bottle, instead of letting it fall on the floor.

For a better understanding of the invention, reference may be made to the accompanying drawing, in which

Fig. 1 is a view in front elevation of the decapper;

Fig. 2 is a view of the decapper in side elevation with the cap on a bottle in position for removal by means of the device;

Fig. 3 is a view similar to Fig. 2 showing the cap retained after release from the bottle;

Fig. 4 is a vertical sectional view of the device;

Fig. 5 is a plan view of the blank used for the base of the device; and

Figs. 6 and 7 are end and side views, respectively, of the magnet employed in the device.

The decapper of the invention comprises a base generally designated 10 and made up of a top wall 11, a pair of side walls 12, 13, and a bottom wall made up of two sections 14a, 14b. The side walls extend downwardly from the lateral edges of the top wall and the sections 14a, 14b are connected to the lower edges of respective side walls. At one end of the base, the top and side walls are provided with laterally extending tabs 15a, 15b, 15c, which lie in a plane and have openings for screws 16, by which the device can be secured to a supporting surface, such as a vertical wall 17. Preferably, the lower edges of the side walls 12, 13 are inclined outwardly and upwardly so that the plane of the sections 14a, 14b of the wall is similarly inclined.

At its outer end, the top wall is provided with a projection 18, which is downwardly and outwardly inclined so as to be at about right angles to the plane of the bottom wall. The projection terminates in a flange 19, which lies opposed to and substantially parallel to the bottom wall. At the inner end of the bottom wall, the sections 14a, 14b are provided with tabs 20a, 20b lying in the plane of the attaching tabs 15a, 15b, 15c. The tabs assist in centering a cap during the decapping operation.

The base is preferably made from a single blank of non-magnetic sheet metal and the blank

2

21 is suitable for the base illustrated and can be converted into the base by being folded along the dotted lines. As will be observed, the outer inclined edges of the blank are formed with cutouts 22a, 22b and, in the completed base, these cut-outs provide an opening in the bottom wall. After the base has been formed, a plug 23 of wood is inserted in the space defined by the top, bottom, and side walls, and the plug is of such shape as to fit snugly within the space with its exposed face lying flush with the inner faces of the tabs 15a, 15b, 15c. The plug is provided with a recess, which lies in alignment with the opening formed by cutouts 22a, 22b, and a permanent magnet 24 is inserted through the opening and into the recess. The magnet has a diametrical slot 25 in its exposed end to provide poles 26, 27, and it also has an axial passage 28, through which a screw 29 may be passed and threaded into the block. Preferably, the recess in the block is of slightly less diameter than the magnet, so that the magnet is held in place partly by its driving fit into the recess and partly by the screw 29.

When the decapper is mounted on a vertical surface, the projection 18 extends downwardly and outwardly, as shown in Fig. 2. When the cap 30 is to be removed from a bottle 31, the bottle is held with the cap lying against the bottom wall of the base, which serves as an abutment, and with the edge of the cap overlying the flange 19 on projection 18. When the lower end of the bottle is swung toward the vertical surface, the cap will be freed from the end of the bottle neck. During the removal operation, the cap is in contact with the end of the magnet and, when the cap has been freed from the bottle and the latter removed, the cap is retained by the magnet, instead of dropping to the floor. The cap can then be removed by hand and dropped into a receptacle, or may remain in place until the next bottle is to be opened.

I claim:

1. A bottle decapper, which comprises a base having means for attachment to a flat surface, an abutment wall lying at an oblique angle to the plane of the attachment means and having an opening, and a projection extending beyond and at substantially right angles to the abutment wall and terminating in a flange opposed to the abutment wall, a magnet closing the opening in the abutment wall and terminating substantially flush with said wall, and means behind the wall for holding the magnet in position.
2. A bottle decapper, which comprises a base

having means for attachment to a surface, an abutment wall, and a projection extending beyond the plane of the abutment wall and terminating in a flange opposed to the abutment wall, the abutment wall having an opening offset from the free edge of the flange, a magnet closing said opening and terminating substantially flush with the abutment wall, and a block behind the abutment wall having a recess into which the magnet projects.

3. A bottle decapper, which comprises a base having means for attachment to a surface, an abutment wall, and a projection extending beyond the plane of the abutment wall and terminating in a flange opposed to the abutment wall, the abutment wall having an opening offset from the free edge of the flange, a magnet closing said opening and terminating substantially flush with the abutment wall, and a block behind the abutment wall having recess into which the magnet projects, and a screw extending through an opening in the magnet and threaded into the block.

4. A bottle decapper, which comprises a base having a top wall, opposed side walls connected to the lateral edges of the top wall, and an inclined bottom wall connected to the lower edges of the side walls, the bottom wall having an opening, a projection extending outwardly and downwardly from the outer end of the top wall and provided with a terminal flange opposed to the bottom wall, and a magnet mounted in the opening in the bottom wall with its outer end substantially flush with said wall.

5. A bottle decapper, which comprises a base having a top wall, opposed side walls connected

to the lateral edges of the top wall, and an inclined bottom wall connected to the lower edges of the side walls, the bottom wall having an opening, a projection extending outwardly and downwardly from the outer end of the top wall and provided with a terminal flange opposed to the bottom wall, means on the base for attaching it to a surface, a block substantially filling the space defined by the walls of the base, and a magnet mounted in an opening in the block and having an end portion within the opening in the bottom wall.

6. A bottle decapper, which comprises a base formed of a sheet metal blank and having a top wall, opposed side walls connected to the lateral edges of the top wall, and an inclined bottom wall formed of two sections connected to the lower edges of respective side walls, the opposed edges of the sections having cut-outs forming an opening, wings projecting from the inner ends of the side and top walls and lying in a plane, a projection extending downwardly and outwardly from the outer end of the top wall and terminating in a flange opposed to bottom wall, and a magnet mounted in the opening in the bottom wall.
